CORPORATION OF NEW YORK.

TURNSTILE.

1,385,971.

Specification of Letters Patent. Patented July 26, 1921.

Application filed November 20, 1919. Serial No. 339,326.

To all whom it may concern:

Be it known that we, CONRAD D. TRUBENBACH and DIETRICH B. SANNEMAN, citizens of the United States, and residents, respectively, of Mount Vernon, in the county of Westchester and State of New York, and of the borough of Brooklyn, city and county and State of New York, have invented a new and useful Improvement in Turnstiles, of which the following is a specification.

This invention relates to turnstiles, and particularly to turnstiles used on railway cars.

The object of the invention is to provide for the registration of each and every passenger who steps inside a car before he can alight therefrom.

Another object is to provide a turnstile that will give a clear or fairly clear space at the exit; so that the passengers will have nothing, or practically next to nothing, in their way when alighting.

A still further object is to provide means by which though two turnstiles are used on the car one on the up trip and another on the down trip but one of these turnstiles will have its arms spread; the other turnstile presenting practically but a post in the way of the outgoing passengers, and therefore will be a convenience rather than a detriment or disadvantage, as the passengers can steady themselves if the car sways or suddenly starts, or even more suddenly comes to a standstill.

With these objects in view the invention consists in certain novel features of construction, and in certain parts and combinations hereinafter to be described and more particularly pointed out in the claims.

Heretofore great trouble has been experienced in accurately registering the exact number of passengers that step into and out of a car, but with the herein described invention no passengers can pass from the car until they have registered their presence in the car by a mechanical device appropriately situated, and which cannot be either tampered with or avoided. Nor will there be any time lost in passing the passengers from entrance to exit; but if any should

try to avoid paying fare the conductor can stop them from passing out of the car through the exit; and of course the motor-man can prevent them from alighting through the door they entered.

This application is a continuation in part of our application filed December 26, 1918, and serially numbered 268,275, now Patent No. 1,339,076, granted May 4, 1920.

In the accompanying drawings, which show an embodiment of the invention:—

Figure 1 is a plan view of the interior of a non-looping or Y-car with entrances at both ends and exits in the middle showing the turnstile casings in their positions; one in its operative position or with the removable head and the arms thereof spread above the casing; and the other in its inoperative position as a mere post without arms or head, and therefore not blocking up the exit.

Fig. 2 is a plan view of the interior of another type of non-looping or Y-car similar to the one shown in Fig. 1, but having the entrances, and exits as well, at the end portions of the car. The turnstile casings are placed one at each end, one being shown with the removable head and arms thereon, and the other without the same.

Fig. 3 is a plan view of the interior of a looping car having the entrance at the forward end and the exit in the center portion thereof. In this view if the head and arms be placed on the turnstile casing shown in the center of the car, the car will be a pay-as-you-travel car; but if they be placed on the turnstile casing shown on the right hand end of the car the same will be a pay-as-you-enter car.

Fig. 4 is a side elevation of the upper portion of one of the turnstile casings with the head and arms removed therefrom showing the squared portion of the shaft, the upper and lower washers and the nut; or as the upper portion of the turnstile casing looks when not in operation as a turnstile, but rather standing immobile as a post for the convenience of the passengers.

Fig. 5 is a similar elevation to Fig. 4 of the same turnstile casing with the removable

head and arms in place and the nut holding the same between the upper and lower washers.

Similar numerals of reference denote similar parts throughout the several views.

The invention is constructed, mounted and operated substantially and preferably as follows:—

1 is a turnstile casing or frame containing 10 the ordinary mechanism 20 used therein as well as the fare register 21. A pair of these casings are fastened solidly to the floor of the car in any desired place or position allowing the upper part of the revoluble shaft 2 to project upwardly therefrom as shown more particularly in Fig. 4.

The projecting portion of the said shaft immediately above the casing has a washer 3 fixed thereto, and above the said washer 20 the shaft is squared off as at 4. Above this squared portion the shaft is reduced as at 5, and a thread 6 is cut on this reduced portion. A nut 7 and a second washer 8 completes this portion of the casing unit.

25 A removable head and arms unit comprising the head 9 and the arms 10 completes the turnstile.

After removing the said nut this latter unit is slipped over the threaded portion 5 30 onto the squared portion 4, and the nut 7 is screwed down and holds the said head and arms firmly between the washers 3 and 8, and makes the head and arms unitary with the said shaft.

35 The machine will now function as a complete turnstile, leaving the other casing 11 standing like a post and not encumbering the exit passageway to any extent.

When the car travels in the opposite direction, the same operation is reversed, the same head and arms unit doing duty for both casings 1 and 11 alike.

In placing the turnstile casings on a car 12, if the same be of the Y-type as in Fig. 1 45 the operative positions of the casings will be on either side of the longitudinal center line C—D of the car, as more particularly brought out in our said companion application; but instead of the turnstile being moved 50 as a whole transversely across the floor of the car as in said companion application, only the head and arms thereof are moved across from the operative position 13 to another operative position 14 on the other side 55 of the longitudinally placed bar 15.

If the car 12 be of the type shown on Fig. 2 the turnstile casings 1 and 11 are placed one at either end of the car as shown, leaving the passageway at the end where the 60 turnstile casing is inoperative almost entirely clear and unimpeded.

If the car 12 be of the non-looping type as shown in Fig. 3 the two turnstile casings 1 and 11 are placed as shown.

65 In Figs. 1, 2 and 3, 17 represents perma-

nent horizontal bars or the like; 18 are movable bars or partitions; and 19 show the position of the tracks on which the said partitions slide as shown more particularly in the said companion application.

The positions shown in Fig. 3 are especially advantageous should the travel be from a point, say a city, to outlying factories. Going out from the city the crowd would be greatest and more concentrated in a constricted space as in the city, and therefore in order not to delay the car the passengers should be allowed to enter the front and pay as they travel filling the rear portion 16 of the car as no passengers would 75 probably get on after passing say the city line.

On returning however, there is not so much chance of delaying the car as only a few passengers at a time get on the car from 80 each of the factories, and these can be required to pay as they enter.

The invention is not limited to just the three types of cars shown for the same can be used in any type of car or even on the 90 ground; and therefore it must be understood that various changes may be made in the form, proportion, size and detail of the several structures shown as well as in the number and position of the different elements 95 used, without departing from the spirit of the invention.

We claim:

1. The combination with a car, of two independent turnstile casings containing 100 registering mechanism, and a single head and arms therefor.

2. The combination with a car, of a plurality of supports, registering mechanism mounted on each of the same, and a single 105 head and arms connected therewith removably mounted upon one of the said supports and adapted to be transferred to and removably mounted upon the other of said supports.

3. The combination with a car, of a turnstile comprising a headless support, registering mechanism thereon, a second and similar support, registering mechanism 115 thereon also, and a revoluble head and arms connected therewith and adapted to be mounted on either of the said supports.

4. The combination with a car, of an entrance at one end and an exit in the middle thereof, and a turnstile having its support 120 mounted directly opposite the said exit.

5. The combination with a car, of an entrance at one end and an exit in the middle thereof, and a turnstile having its support mounted directly opposite the said exit and 125 against the farther side of the car opposite the said exit.

6. The combination with a car, of an entrance at one end and an exit in the middle thereof, a turnstile having its support 130

mounted directly opposite the said exit and against the farther side of the car opposite the said exit, and a bar placed approximately along the longitudinal center line of 5 the car between the said turnstile and the said exit.

7. The combination with a car, of an entrance at one end and an exit in the middle thereof, a turnstile mounted opposite the

said exit and against the farther side of the car opposite the said exit, a bar placed approximately along the longitudinal center line of the car between the said turnstile and the said exit, and a second bar placed over the top of the said turnstile and parallel to 15 the said first mentioned bar.
